UNITED STATES PATENT OFFICE.

MARTIN L. NELSON, OF PARK RIDGE, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TESTING EQUIPMENT FOR AUTOMATIC TELEPHONE SYSTEMS.

Application filed August 10, 1925. Serial No. 49,226.

This invention relates in general to testing equipment for automatic telephone systems, more particularly to testing equipment for testing the directors which register, translate and retransmit the digits of telephone numbers.

Specifically the invention relates to improved director test mechanism which automatically applies a series of tests to a series of directors and which intercepts the digits that the director sends out and records them as received properly or improperly.

In the so called director system, a relatively small number of directors are employed in common to a group of trunks to register, translate and retransmit the digits of telephone numbers. As soon as these digits have been retransmitted, the director disassociates itself from the trunk and cannot be readily further identified with the pending call, making it very difficult to determine just which director is not functioning properly. Therefore it is imperative to good service that the directors be kept in first class condition so that their performance will be accurate and reliable. The best known way of keeping such equipment in reliable order is by routining it, that is, by frequently applying characteristic tests, which, if properly executed indicate that the equipment is functioning properly. The director has many functions to perform, and in order to definitely determine that the mechanism is performing all the functions properly, a large number of separate tests must be included in the routine. If these tests are applied manually, a considerable period of time is required for each director and the maintenance costs are therefore made unduly high.

Accordingly, the principal object of this invention is the provision of a director routine test mechanism which will automatically routine a group of directors without attendance, other than that required to start the mechanism and to record and repair the faults found.

A further object is to provide a testing mechanism which seizes each director in its consecutive order, applies a test to it and if the test is properly completed, releases that director to common usage and seizes the next, on which the same test is applied.

Another object of this invention is to provide a testing mechanism which is arranged to camp on a busy director, if that director is engaged in setting a call, and to skip a busy director, if that director is made permanently busy by means of the director busy key provided for the purpose.

A still further object of this invention is to provide a testing mechanism arranged to apply a large number of tests to each director, and still further arranged so that it changes from one test to another after the former test has been applied to all of the directors in the group.

A still further object of this invention is to provide a testing mechanism which, when a fault is found will indicate which director defaulted, and the exact nature of the fault, and which will hold the director and test mechanism in place while a signal is sounded to summon the attendant to the mechanism to locate and repair the fault.

A further object of this invention is to provide a test mechanism which will exercise a director, that is, repeat the same test on any director indefinitely, to make sure that that mechanism functions properly.

A still further object of this invention is to provide a test mechanism, which will routine a single director, that is, run all of the routine tests on a director to make sure that that mechanism is functioning properly.

Further objects of this invention which are not specifically enumerated here will be apparent from the detailed description and claims which follow.

The drawings comprising Figs. 1 to 10, inclusive, when arranged as shown in Fig. 11, show sufficient details to enable a clear understanding of the construction and operation of my invention.

Figure 1 shows a director mechanism together with the trunk circuit which renders it available to the director selector and to the test mechanism.

Figure 2 shows the test director selector, which connects with the directors to be tested and controls the application of tests thereto.

Figure 3 shows the test sender mechanism by which a certain number is sent into the director to set the mechanisms therein in their proper positions to perform the desired tests.

Figure 4 shows the test selector mechanism which determines which of the several tests will be applied to the director that is being tested.

5 Figure 5 shows the test sender control relays comprising two groups, one group which controls the digits and the other group which controls the impulses in the digits.

10 Figure 6 shows the test set-up relays A by means of which it is determined what number will be sent into the director and what number must be received from the director by the test mechanism, in test A.

15 Figure 7 shows the receiver control relays which count the impulses received from the director to determine whether or not the translated number has been properly sent by the director. This drawing also 20 shows the impulse lamps numbered consecutively from 0 to 11, inclusive, by means of which a fault is located.

25 Figure 8 shows the receiver digit control relays by means of which the digits to be received are determined in cooperation with the set-up relays of Fig. 6 and also the digit lamps by means of which the fault is located with respect to the digits.

30 Figure 9 shows a second test set-up relay group hereafter designated as test C, which is arranged to replace Fig. 6 and to control the sender and receiver mechanism when test C is being made in a manner which will be explained more fully hereinafter.

35 Figure 10 similarly is another test set-up control, hereafter designated as test D, which is arranged to replace Fig. 6 and to control the sender and receiver mechanisms when test D is being transmitted as will be explained hereinafter.

40 In an actual installation I propose to multiple the digit and impulse wires from the sender control relays, shown in Fig. 5, to a plurality of terminal pins on the sender IDF shown in Fig. 6, and in a similar manner to multiple the impulse and digit wires from the receiver control relays shown in Figs. 7 and 8 to a plurality of terminal pins on the receiver IDF shown in Fig. 6. The test set-up relays A, shown in Fig. 6 are connected to one set of terminal blocks, both in the sender and receiver IDF's, and similarly the test set-up relays of Figs. 9 and 10 are connected to other terminal blocks of both distributing frames, so that one of three test set-ups govern the setting of the sending and receiving controls, dependent upon which test control relay group is energized. In order to avoid undue complication of 50 the drawings by including all of these multiples from the plurality of counting relays, I have arranged the drawings so that the test set-up to be used is shown directly connected to a single terminal set in the distributing frame, and when another test is to

be explained, the drawings showing that test set-up is substituted for the former drawing, it being understood that this arrangement does not designate an alternative test means, but is merely an arrangement to simplify the drawings as much as possible.

It should be noted that I have shown in Fig. 6, three sets of normally closed springs, 922, 1024, 1045, that are not associated with any relay; the two latter springs also appear in Fig. 9, and the former in Fig. 10. I have chosen to show certain circuits in this manner in connection with the above mentioned plan of drawing simplification. The springs 922 are a set of break springs on relay 903 of test C. Except when test C is being employed, these springs are closed to connect the director selector step conductor 1 to the director selector step conductor 2. Similarly the springs 1024, which are in the relay 1009 of the test D connect the start conductor to the start 1 conductor except during the application of test D. Also the pulse 1 conductor and the pulse 2 conductor are joined together through springs 1045 except when relay 1007 is energized during test D. These springs that are shown detached from their relays, remain closed throughout the application of the test in which they are so shown, and may be regarded as a solid connection during the consideration of that test.

Throughout the drawings, in order to avoid undue complications, I have shown a plurality of batteries whereas in reality there would be but one battery, preferably with its positive pole grounded.

Referring now to Fig. 1 in more detail. I have shown a skeleton of a director mechanism such as is disclosed in full in my co-pending application Serial No. 719,459, filed June 12, 1924. This mechanism which is common to a trunk group is accessible thereto through the medium of the director selector, and is operable to register, translate and retransmit the digits of telephone numbers. Provided with each director is a director busy key by means of which that director can be made permanently busy and inaccessible to the director selectors in the well known manner by placing ground potential on the private or testing conductor.

In Fig. 2, I have shown a test director selector which is a director selector similar to the regular director selector indicated in Fig. 1 by means of which the testing mechanism is connected to the directors to be tested. With the director selector arranged as shown in Fig. 2, a maximum of 24 directors can be made available to the test mechanism, the twenty-fifth contact of the group being utilized for other purposes, as will be apparent hereinafter. It will be understood that it is by way of example that I have chosen this arrangement and that by

the use of a secondary switch, a maximum of 576 directors can be made available to the test mechanism.

Briefly, the operation of my invention is as follows: when the attendant starts the test mechanism by operating certain keys, the test director selector steps its wipers on to the trunk leading to the first director of the group. If that director is engaged at the time setting up a call, the test director selector camps there, lighting a lamp, indicating that the director No. 1 is busy. As soon as that director becomes idle, the test director selector seizes it and makes it busy to the regular director selector so that the test will not be interfered with. Simultaneously with the starting of the test director selector, the attendant operates the key to start the test sender impulsing relay in operation and to step the test selector into connection with the first bank contact, so that the testing mechanism is arranged to send out the first test, which is test A. The test set-up for the first test is shown in Fig. 6, the relays 601 and 602 being energized through the banks of the test selector of Fig. 4, to connect up the sender and receiver counting relays in accordance with the digits of the first test. In this test the testing mechanism is arranged to send in to the director the digits 431 in response to which the director sends out the digits 3431. In sending the digits into the director the test sender impulses in the well known manner to send ground impulses over the impulse wire to the director, the number of impulses being counted by the counting relays, which are arranged to cut off the impulsing when the proper number of impulses have been sent, in this case 4. At the end of the first digit, the sender digit control relays function to connect the impulse counting relays so that they will count out the correct number of impulses for the second digit, in this case a 3, that digit being transmitted into the director in the same manner as was the first digit. In a similar manner the remaining digits are sent to the director.

After the impulses have been transmitted into the director mechanism, it starts to send out over the loop conductors a series of digits, the nature of which is dependent upon the register mechanism setting of the director itself, as explained in detail in my above mentioned copending application. Responsive to the pulsing by the director, the test set mechanism pulsing relay is operated to transmit impulses of ground to the receiving counting relays, setting up a combination of counting relays in accordance with the number of impulses received from the director. At the end of the transmitting of the first digit the test set mechanism makes a test to determine whether or not the digit received was the digit that should be

received, that test being made by projecting ground out on the fault wire which is extended through the first combination of the receiver impulse and digit counting relays back to the test conductor. If the digit was properly received, the digit control relays of Fig. 8 are operated to prepare the receiving mechanism for reception of the second digit of the call number.

When the test set-up relays 601 and 602 are energized to put the sender and receiver mechanisms of the test set under the control of test set-up A, the sender mechanism is arranged to send in to the director the digits 431, responsive to which the director must send out the digits 3431. If, for any reason, the director sends out a wrong digit, the test loop mentioned previously will not be completed through the counting relays since those relays will be improperly set, and as a result the test director selector will lock up holding the faulty director to prevent its seizure by a subscriber, and the test lamps will be lighted to indicate the nature of the fault. If, for example, the director sent out a first digit of 4 instead of 3, director No. 1 being tested at the time, the test lamps would be lighted to indicate that director No. 1 had defaulted and that it had defaulted on the first digit sending out a 4 as the first digit. By reference to the test chart or any suitable record, the attendant knows that the first digit should be a 3. Inasmuch as the test director selector is holding the faulty director in its operated position, the attendant can examine that director in detail to determine the cause of the fault. The attendant, upon finding the trouble, may repair the same, and in order to make sure that he has properly repaired the director, he will operate a so called consecutive test key on the test set mechanism. Operation of the consecutive test key arranges the circuits of the test director selector so that the test then being applied is repeatedly applied to the same director, in this case director No. 1, to exercise that director so that the attendant may make certain that it is functioning properly.

When the attendant is certain that the director No. 1 is functioning properly he reoperates the consecutive test key, whereupon the test is repeated on the director No. 1 once more and if the test mechanism receives the proper combination of digits, the test director selector at the end of the test selects out and picks up director No. 2, and if that director is not busy at the time in the process of setting up a call, it immediately receives the same test on it. At the end of that test the director selector steps on in search of director No. 3, which for the moment will be assumed to be made busy by means of the director busy key. In this case the test director selector will not camp

on that trunk, but will advance immediately and pick up director 4, for the reason that director No. 3 is probably made busy because of some fault already known to the attendant and there would be no advantage gained in testing the director.

After the entire group of directors have been tested with the test A, as explained hereinbefore, the test selector shown in Fig. 10, 4, immediately after the completion of the test on the 24th or last director of the group, advances its wipers one step to change the test set up relay, that is, to pick out a new test to be applied to the group of directors.

15 In Fig. 4 I have shown the test A applied to the directors when the wiper 411 is in the first six positions of its bank. And the test B applied to the director when the wiper 411 is in the second 8 positions of its bank, and 20 the test C applied to the directors when the wiper is in the third 5 positions of the bank with the test D applied only once as will be obvious from the bank connection. I have made this particular set-up of the 25 selector merely by way of example as it is possible to apply 25 different tests one for each bank contact encountered by the wiper 411. The test A shown on test set-up Fig. 6, is the most simple test that can be applied 30 to the director, exercising the most simple function of the director, in which case digits are impulsed into and a greater or lesser number of digits sent out by the director mechanism. Test B, which is selected when 35 the wiper 411 of the test selector reaches the second group of bank contacts, may be substantially like test A and need not be explained in detail here.

When the wiper 411 reaches the third 40 group of bank contacts, it picks out the test C, which is shown in test set-up Fig. 9. With Fig. 9 substituted for Fig. 6 between Figs. 5 and 7 and to the right of Fig. 3, the drawings are arranged to show the circuits of the test set when the test C is being made. It will be noted that the circuit is completed from the wiper 411 of the test selector through the test control conductor C to the windings of the relays 901 and 902, 45 energizing those relays to place the sender and the receiver mechanisms test set under the control of the test C. This set is arranged to impulse into the director 111 and to receive from the director the digits 111 50 followed by a director cutoff. The test set up is further arranged so that the above mentioned test is repeated twice on each director before the test director selector steps on to pick out the next idle director. Be- 55 cause of the peculiar setting of the director digit registers when the digits 111 are recorded, there is a possibility that these registers will not restore to normal properly when the director cuts off, particularly if one 60 of the digit registers happens to be a little

sluggish in releasing. In order to catch failures of this kind it is necessary to repeat the test upon the director before releasing it to common usage. If, for example, the digit register recording the third 1 of the called 70 number had failed to release properly when the director was called upon to call that number again, the third digit of the number would contain two impulses instead of one. When the digits were received by the test 75 mechanism this error in the third digit of the number would be recorded as an indication to the attendant that the digit register of the director was sluggish to release. The attendant would then repair the fault and exercise the director several times to make certain that he had properly adjusted the faulty mechanism, before proceeding with the test, as set forth before. Aside from this change the test set-up C is an exact 80 duplicate of the test A and need not be explained in further detail at this time.

When the wiper 411 of the test selector reaches the bank contact to which is attached the test control conductor D, the circuit is 85 completed to the test set-up relays 1001 and 1009 of Fig. 10, to bring the sender and receiver mechanisms of the test set under the control of the test D. By substituting Fig. 10 for Fig. 6 between Figs. 5 and 7 and to 90 the right of Fig. 3, the drawings are arranged to show the circuits of the test mechanism when the test set-up D is employed. The test D is arranged to test the time limit release of the director mechanism.

Inasmuch as there are but a comparatively few directors employed in an exchange it is necessary to take steps to prevent the monopolization of the director either intentionally or through accident. If a receiver 105 were to be accidentally taken off the hook, the line switch mechanism of the telephone exchange would function to seize the director in the well known manner, and if no impulses were received by that director it would not move out of normal and would become permanently out of service. Or, if a subscriber started to call a number and after dialling one or two digits, he forgot the rest of the number or neglected to dial it, 110 the director again would be tied up as sufficient number of digits to release it have not yet been received. To guard against contingencies of this kind, a time limit pulse is provided which, after a definite interval, 115 if no impulses are received by the director, causes the director to release the established train of switches and to dial a predetermined number, which may either return a busy tone to the subscriber or connect the subscriber to a supervising operator. The test D is arranged to determine whether or not this function is being properly performed. In this test the sender of the test mechanism dials a 99 into the director and then waits. 120

The director sends out a 9 and then waits. At the end of an interval the time pulse sent out by the time pulse mechanism operates both the director and the test set mechanism, 5 causing the director to release and send back the digit 1. The time pulse received by the test set mechanism test set-up D, arranges that test set so that if the digit 1 is received immediately following a release by the director, the test will be recorded as correct.

When the wiper 411 has reached the last groups of contacts in the bank of the test selector, it closes a circuit to the relay 401, which energizes to sound the signal 412 15 and to light the lamp 413 to notify the attendant that the routine has been completed on all of the directors and that the test is ended.

In the testing sender, shown in Fig. 3 is an 20 interrupting relay 301 which is arranged to impulse into the director mechanism. In order that the test may be successfully carried on, it is necessary that this relay be maintained in standard adjustment, so that the 25 impulses received by the director mechanism will be the same as are received by the director from the director selector when the director is being used to set up a call. For this purpose I have provided the jack springs 320 and 321 by means of which I can connect a testing mechanism such as shown in my copending application, Serial No. 744, 528, filed October 18, 1924. By operating the keys 322 and 323 I am able to divert the 30 impulses delivered by the springs 325 of the interrupting relay into the test mechanism disclosed in the above mentioned application. This mechanism is arranged to determine the speed and impulse ratio of the impulses, 35 and serves as a guide in the adjusting and timing of the standard interrupting relay 301 of the test sender.

It may happen that the attendant, after 40 repairing one of the director mechanisms, 45 may desire to place a particular one of the tests on the director he has repaired, and to repeat that test a plurality of times on that director to limber up the mechanisms he has repaired. He may do this by starting the 50 test mechanism in the above manner, and then by manually stepping the director selector to the desired director by operating the director selector step key 234, and then step the test selector to the desired test by 55 operating the test selector step key. He will then operate the consecutive test key 241 to the position in which it exercises the director. In this manner the attendant is able to put a working test upon the parts of the 60 director that he has repaired or replaced, and by this means he is able to definitely determine whether or not he has put the director mechanism in its proper working order.

In the event that the attendant desires to

place all of the routine tests on the director that he has repaired, he arranges the testing mechanism to exercise the director, and in addition operates the director routine key 226. The circuits are then arranged so that at the end of a successful test, the 70 ground pulse that normally would operate the director selector motor magnet 212 is diverted to the test selector motor magnet 404, energizing that magnet to advance the wipers 410—411 one step. By this arrangement all 75 of the tests in the routine are applied to the single director.

Having thus described my invention in general, I will now proceed with a detailed description of its operation as it places the 80 various tests upon the directors. First, I shall explain the detailed functions as the test A is applied to the directors.

Starting the test mechanism.

In order to start the test mechanism in motion, the attendant first operates the interrupter start key 324, closing the circuit from ground through springs 324 to the winding of interrupter relay 301 and the 90 winding of relay 303 in series to grounded battery. The relay 301 energizes over this circuit and attracts the armature 302 to close the contacts 302 and 326, thereby shunting out the winding of relay 301 and providing 95 a direct path from grounded spring 324 through springs 302 and 326 to the winding of relay 303. Relay 303 being marginally adjusted will not energize in series with relay 301, but will energize when the latter 100 relay is shunted out. Relay 301 being shunted out deenergizes after a moment allowing the armature spring 302 to retract to operate the springs 325. As soon as relay 301 has removed the short circuit from itself, relay 105 303 deenergizes, closing the spring 327 for a purpose which will be explained hereinafter. Relay 301 again attracts its armature 302 and shunts itself out to energize its relay 302 and deenergize itself as before. Because 110 of the weight on the armature 302, its movement is pendulum like and timed to vibrate at the rate of 10 per second so that the spring 325 and the relay 303 are both operated at the rate of 10 operations per second. After 115 having started the impulsing relay in motion the attendant then operates the test step key 419, closing a circuit from ground to springs 419 through the winding of relay 404 to grounded battery. The relay 404 energizes and prepares to advance the wipers 410 to 411 one step. This switch mechanism being of the well known rotary line switch type, advances its wipers when the motor magnet 404 deenergizes rather than when 120 the magnet is energized. When the attendant releases the key 419 magnet 404 deenergizes advancing the wipers 410 and 411 125

6
to the first bank contact in which position the wiper 411 is in contact with the bank contact "a". A circuit is then closed from ground through key 420 and its break contact, springs 417, wiper 411, now in contact with bank contact "a", test control conductor A, through the windings of relays 602 and 601 in series to grounded battery. Relays 601 and 602 energize over this circuit, thereby preparing the test sender and test receiver controlled to send out the test A.

Test set-up A.

Relay 602 upon energizing closes a circuit 15 from ground through springs 614 and its make contact, through the start 1 conductor, through break contacts 1024 through the start 2 conductor through the break contacts of fault release key 261, through break 20 contacts 254, through the winding of relay 204 to grounded battery. Relay 204 energizes over the above traced circuit and at spring 242 closes a circuit from ground through springs 242, spring 235 and its break 25 contact, through the winding of relay 201, through spring 232 and its break contact through the wiper 223, now assumed to be in connection with the bank contact to which private conductor 451 is connected, over conductor 451 through the winding of relay 806 30 of the director to grounded battery. Relay 806 of the director and relay 201 of the test director selector energize over this circuit, the former to start the interrupter relay 811 35 of the director mechanism, and the latter to seize the director, and to connect it to the test mechanism.

Seizing the director.

40 Relay 201 upon energizing at spring 232 and its make contact puts direct ground upon the private conductor 451 leading to the director C, and making that director busy in the banks of the director selector. At springs 230, 231, and 233, the relay 201 closes a circuit connecting the trunk conductors of the director to the test set mechanism. The director is now seized and under the control of the test set 45 mechanism, a circuit being traceable from ground to the lower winding of relay 205 through springs 233, through wiper 224, through trunk conductor 450, through the springs 859 of the director to trunk conductor 449, through the wipers 221, springs 231, through the upper winding of relay 205, to grounded battery. Relay 205 energizes over the above traced circuit and at springs 244 50 closes a circuit from ground through spring 260 and its break contact, through spring 244 and 244', through spring 246 and its break contact, through the winding of relay 206 to grounded battery. Relay 206, upon energizing at springs 248 and 247,

closes a point in a circuit through the pulse 65 wire and release test wire, respectively, without effect at this time inasmuch as the conductors are held open in the test set-up control. Relay 206 at spring 245 closes a circuit between the start 1 conductor and the sender start conductor thereby closing a circuit from ground at spring 614 and its make contact over start 1 conductor through springs 245 to the sender start conductor, through springs 332, through the winding 70 of relay 304 to grounded battery, with a parallel branch leading over the hold 2 conductor to the terminals of relays 523, 525 and 527 of the sender digit control. Relay 304 energizes over this circuit and prepares the test sender for impulsing. The interrupter springs 325 at the present time are short circuited by means of the springs 332, a circuit being traceable from the make contact at spring 332 through key springs 323 75 and its break contact, through interrupter springs 325, through key spring 322 and its break contact, through normally closed contacts controlled by spring 334, to the main 80 spring 332. 90

The test sender impulsing.

When the relay 303 energizes in the manner hereinbefore described, it closes a circuit from ground through the sender start conductor, normally closed contacts controlled by spring 334, through spring 327 and its break contact through spring 330 and its break contact, conductor 340, spring 531, through the winding of relay 500 to 95 grounded battery. Relay 500 energizes over the circuit and at spring 530 locks itself to the holding conductor 543 in series with relay 501. The relay 501 does not energize at this time for the reason that there is 100 ground potential on both ends of its winding, one ground being traceable from grounded spring 331 and its break contact, conductor 343 and the other ground through spring 530 to the circuit just traced for relay 500. When the armature 302 of the interrupter relay 301 short circuits that relay, relay 303 energizes and at spring 327 105 opens the energizing circuit of relay 500 which is locked in series with relay 501. 110 Relay 501 then energizes over a circuit from ground through holding conductor 343 through relay 501, through spring 530, relay 500 to grounded battery. Relay 501, upon energizing, at springs 532, closes a circuit from ground through said springs through conductor 341, through the winding of relay 306 to battery. Relay 306 energizes over the above traced circuit and at spring 115 332 opens the previously traced circuit for relay 304 and removes the short circuit from the impulse springs 325 of the interrupter relay 301. The sender mechanism is now 120 125

in position to send out the first digit of the called number, that digit being determined by the sender IDF jumpering and controlled by the test set-up relays 601 and 602.

5 *The sender impulses into the director.*

It will be noted that the first impulse sent out by the interrupter relay 301, after the sender ground has been received by the test 10 sender, is absorbed in the relays 500 and 501, the second impulse being the first one that is effective to control the digit registers of the director. The reason for this is to make sure that the impulses sent in to 15 the director are standard, by absorbing the first three impulses in relays 500 and 501, the possibility of a short impulse is entirely removed. Relay 301 by short circuiting itself to allow relay 303 to energize as has 20 been previously explained, closes the springs 325 in the well known manner, closing a circuit from ground on sender start conductor through key spring 322 and its break contact, through spring 325, through spring 323 25 and its break contact, through the winding of relay 304 to grounded battery. The relay 304, which was energized over a circuit including springs 322 is held energized over the circuit just traced, that circuit being 30 completed before the springs 322 are opened. When the relay 301 deenergizes it breaks at springs 325 the above traced circuit of relay 304 allowing that relay to restore, closing the circuit which is traceable from 35 grounded spring 532 over conductor 341, through spring 328 and its break contact over the impulse conductor, through spring 259 and its break contact, through springs 230, through the wiper 220 to the impulse 40 conductor 452, through the winding of relay 702 of the director, through the wiper 719 and the primary office register motor magnet 909, to grounded battery. The relay 702 and the motor magnet 909 energize over 45 this circuit to register the impulse in the director mechanism in the well known manner. When the relay 301 reattracts its armature, relay 303 deenergizes closing a circuit from grounded sender start conductor 50 through spring 327 and its break contact, through spring 330 and its break contact, conductor 340 through spring 531 and its make contact, spring 534 and its break contact, through the winding of relay 502 to 55 grounded battery. Relay 502 energizes over this circuit and at spring 533 prepares a locking circuit for itself in series with the relay 503. Relay 503, however, having ground on both ends of its coil does not energize at this time. When the armature 60 of the pulsing relay is attracted it closes springs 325, thereby closing the previously traced circuit for the relay 304, which energizes and opens the previously traced circuit of the relay 702 and the motor magnet 65

909 of the director mechanism. The motor magnet 909 falls back when its circuit is open, but the relay 702 being slow acting because of the copper slug on its core, remains in its energized position during 70 pulsing. When the relay 301 has again shunted itself out, relay 303 energizes and at spring 327 opens the previously traced circuit of relay 502 thereby removing the ground from one terminal of relay 503, permitting that relay to energize over a circuit from grounded holding conductor 343 through relay 503 through springs 533, through the winding of relay 502 to battery, locking up the relays 503 and 502. Relay 80 85 90 95 100 105 110 115 120 125 130 503 closes the springs 535, which test the first impulse pin 1 of the sender IDF to see whether or not the first digit to be dialled is a 1. The test set-up A is arranged to transmit the digits 431, so that the first digit to be transmitted is a 4. The impulsing relay again opens the spring 325 to send another impulse of ground to the motor magnet 909 of the director and to permit the relay 303 to again deenergize to send an impulse of ground to the magnet groups 504 and 505, counting off the second impulse of the digit.

End of first digit. 105

This impulse continues until four impulses have been sent to the director mechanism. When the relay 509 energizes at the end of the fourth impulse, it closes a circuit from ground through spring 571 and its break contact to the digit conductor 1, through the jumper to the digit pin 1^a on the sender IDF, to spring 613 of the test set-up relay 601, to the sender pin 1^b, through jumper 1^b-4 on the sender IDF to the fourth impulse pin, through spring 544 and make contact over conductor 342, through the winding of relay 305 to battery. Relay 305 energizes over this circuit and at spring 329 closes the obvious holding circuit for the pulsing relay 304, which remains energized and at spring 328 holds open the impulsing circuit to the director thereby preventing the sending of further impulses to that mechanism. The operation of relay 509 to close 110 spring 544 also projects the ground previously traced from the spring 571 to spring 544 over a path including the digit cutoff conductor to spring 570 and through its break contact, through the winding of relay 526 to grounded battery, energizing the relay 526 which prepares a locking circuit for itself in series with relay 527 at spring 569. Relay 527 of the digit control group is prevented from energizing by having ground 115 on both ends of its coil in the manner similar to the second relay of the impulse counting group. Relay 305 upon energizing locks itself to ground through spring 331 and its make contact, through springs 333, through 120 125 130

relay 305 to grounded battery. Relay 305 upon energizing at spring 331 interrupts the previously traced circuit to the holding conductor 343, thereby allowing the energized impulse counting relays to deenergize. When the impulse counting relays deenergize, ground is removed from conductor 340 by the deenergization of relay 501, thereby opening the circuit of relay 306, which deenergizes after an interval, removing ground from conductor 342 by the retraction of springs 333. Ground being removed from the digit cutoff conductor 342 relay 527 is no longer short circuited and it energizes in series with relay 526, locking itself in energized position to the hold-2 conductor ground. The restoration of relay 306 recloses the springs 332 to short circuit the interrupter springs 325 to maintain the relay 304 energized after relay 305 has restored and opened springs 329. The restoration of relay 305 also completes at springs 330, the previously traced circuit to relay 500, controlled through springs 327 of the relay 303.

The next impulse sent by the sender is absorbed in the relays 500 and 501 hereinbefore explained, relay 501 upon pulling up closing a circuit to spring 532 to the winding of relay 306 to remove the short circuit from the impulse spring 325 to allow impulses to be sent to the pulsing relay 304 as previously described.

Sending the second digit.

When the relay 527 energizes, at spring 571 it removes the ground from the first digit wire which has been previously traced through the sender IDF to the impulse counting pin 4, and closes circuit traceable from ground through spring 571 and its make contact, 568 and its break contact, digits pin 2 through the sender IDF and spring 612 of the relay 601, through the second digit sending pin 2^b of the sender IDF and thence through the jumper to the third impulse pin, which is connected through the spring 541 to the digit cutoff wire. The set-up determines that the second digit transmitted by the test sender is to be a 3. In the director, at the end of the transmitting of the first digit, the relay 702 deenergizes after a brief interval and close circuits by means of which the wiper 719 was transferred from the first bank contact to the second, thereby changing the circuit so that the second set of impulses will be delivered to the secondary office register motor magnet 910 rather than to the magnet 909. The transmitting of the second digit by the test sending equipment into the director duplicates the process just described in connection with the first digit and need not be explained in detail. At the end of the transmitting of the second digit the ground

is supplied to the digit cutoff conductor when the springs 541 are energized after the third impulse, and the digit control relays 524 and 525 energize in a manner similar to that described for relays 526 and 527, transferring the digit cutoff ground from the second digit conductor to the third digit conductor, supplying that ground over the obvious circuit including spring 611 to the first impulse spring and then to the springs 535 of the impulse counting relay 503. In the director at the end of the second digit the relay 702 deenergizes for a brief interval and causes the wiper 719 to be moved to the third bank contact thereby completing the circuit so that the third digit received by the director will be transmitted to the first digit register, in the manner explained in detail in my first above mentioned copending application.

Transmitting the third digit.

The sending mechanism having completed sending the second digit, restores the counting relays to normal, and restarts the impulse sending, is in a position to send out the last digit of the call number 431, in this case a 1. The sending of the 1 is identical with the sending of the previously explained digits and need not now be described.

Sender cutoff.

At the end of the sending of the last digit of the call number the relay 523 of the digit control group energizes in the manner similar to that previously explained for the relay 527, closing a circuit from ground through springs 571, 568, 565 and their respective make contacts over the fourth digit control wire 4, which is jumpered to pin 4^a and connected through spring 610 to pin 4^b, through the jumper to the stop conductor, thence over the stop conductor, through relay 307 to grounded battery. Relay 307 energizes and at springs 334 opens the start ground circuit to the impulse sending mechanism, thereby removing ground, which was supplied to the test sender over the sender start conductor, from the sending mechanism, definitely preventing the sender from transmitting any more impulses to the director. Relay 307 upon energizing locks itself to the grounded sender start conductor over spring 334 and its make contact, thereby holding itself in energized position independent of the grounded spring 571. Relay 307 upon energizing removes the ground from the hold 2 conductor, thereby unlocking the energized relays of the digit control group, restoring them all to normal in readiness for transmitting of the next number by the sender.

The director starts impulsing.

The director outgoing loop circuit, now connected to the relay 205 over a circuit in-

cluding the spring 854 of the director mechanism, also includes a parallel circuit including conductor 449 to interrupter spring 813, thence back to conductor 450. When the 5 director is in position to transmit the first digit the short circuit of the interrupter springs 813 by the springs 854 is removed and the springs 813 begin opening the loop circuit of relay 205, causing that relay to im- 10 pulse and send out the first digit. At the end of the first digit the springs 856 are closed to stop the impulsing by again short circuiting the impulsing springs, in the well known manner that is explained in detail in 15 the first of my above mentioned copending applications. In the test director selector the relay 205 upon falling back opens the previously traced circuit of relay 206, without effect at this time owing to the fact that 20 relay 206 has locked itself to ground over its circuit from grounded key spring 239 and its break contact, through springs 238, through hold 4 conductor, through spring 246 and its make contact, through the winding of relay 206 to grounded battery. Relay 205 upon falling back also closes a circuit from ground through spring 260 and its break contact, through spring 244 and its break contact, through springs 248 to the 25 pulse conductor, through spring 764 and its break contact, through the winding of relay 712 to grounded battery, with a parallel branch, through spring 1045 to conductor 775, through spring 763 to the test relay con- 30 ductor, thence through the winding of test relay 207 to grounded battery. Relays 207 and 712 energize over this circuit, the latter at spring 752 forming a locking circuit for itself in series with the relay 701, which is 35 connected to the grounded hold conductor. Relay 701 does not energize at this time for the reason that the ground on the pulse conductor short circuits the relay. Relay 207 upon energizing at spring 250 closes a circuit from grounded start conductor through the fault release key 261, through spring 254, spring 250 and its make contact to the winding of relay 209. Relay 209 upon energizing locks itself to the fault release conductor through spring 253 and spring 258, independent of the spring 250. At the end of the first impulse the relay 205 energizes again opening the previously traced circuit to relays 712 and 207. Relay 207 being slow 45 to release because of the copper slug on its core, remains energized during impulsing. When the ground is removed from the pulse wire, relay 701, which was short circuited by that ground is no longer short circuited and energizes over a circuit from the 50 grounded holding conductor through relay 701 through springs 752, through the winding of relay 712, to grounded battery. Relay 701 upon energizing extends the pulse 55 wire to relays 702 and 713, and extends the fault wire through springs 730 to springs 731, and at springs 741 extends a lamp ground conductor to springs 742. The director now being tested is arranged to send out the digits 3431 when the digits 431 are sent into it. The interrupter relay 803 will therefore open the circuit of pulsing relay 205 three times, the first impulse having been explained, the second impulse will lock up 60 relays 702 and 713 in a similar manner and the third impulse will lock up relays 703 and 714. The fault conductor will now be connected through springs 730, 731, and 732 and their respective make contacts to springs 733, and the lamp ground will be connected through springs 741, 742, and 743 and their respective make contacts to the springs 744, and the pulse wire will be connected through springs 764, 765, and 766 and their respective make contacts to the springs 767. 65

Testing the digit received.

When the spring 856 of the director short circuits the interrupter springs 813, the relay 205 comes to rest energized, opening the 70 circuit of test relay 207, which restores after a brief interval and closes the test circuit, which may be traced from grounded start conductor through the fault release key 261 and thence over the previously traced circuit 75 to the spring 250, which is now resting against its break contact, through the springs 255, and thence over two paths in parallel, the one through the winding of relays 211 and 210 in series to grounded negative battery, and the other over the fault conductor, which has been traced to spring 733 now resting against its break contact through the third impulse wire of the receiver IDF, now 80 jumped to the first digit pin 6, through spring 617 and its make contact to the first digit pin 1^a, through the jumper to digit pin 1, thence over the digit 1 conductor to springs 822, through spring 822 and its break contact to the test conductor, through 85 the receiver IDF through spring 616 and its make contact to the junction point between relays 210 and 211. The impulse having been correctly received, relay 211 is now 90 short circuited, ground being present on both terminals, and that relay therefore does not energize. Relay 210, energizes over the circuit just traced including the test conductor and at springs 268 opens the locking circuit of relay 209, allowing that relay to restore. 95 Simultaneously with the establishment of the just described circuit to relay 210 a parallel branch is established from the digit 1 conductor through springs 821 to the winding of relay 805 to grounded battery. Relay 100 805 energizes over this circuit and at springs 824 prepares a locking circuit for itself in series with relay 801. Relay 801 being short circuited at this time by having ground potential on both terminals is prevented from 105 110 115 120 125 130

energizing. When the relay 290 energizes it opens the previously traced fault and testing circuit at springs 255, removing the short circuit from relay 801 which then energizes in series with relay 805 and breaks the test circuit at springs 822 and its break contact. Deenergization of relay 801 breaks the previously described testing circuit from the digit 1 conductor, and extends the digit 2 conductor through springs 820 to the second digit control relays 802 and 806, and extends the test conductor through spring 822 and its make contact to the second digit control wire to spring 827. Relay 209 upon deenergizing at springs 256 breaks the holding circuit for the receiver impulse counting relays 701 to 714, which were energized and locked to the hold conductor in counting off the first digit, thereby restoring the test set to normal in readiness for the reception of the second digit which in this case will be a 4.

A fault on the first digit.

In the event that the director had failed to send out a 3, for the first digit of the call number, when the test relay 207 energized and the fault and test circuit was established, the relay 211 would not have been short circuited for the reason that the fault wire would not have been connected to the test wire over the loop circuit previously described. Assume for the moment that the director had sent out a 4 for the first digit instead of a 3. The fault wire would have been connected through springs 733 and its make contact to the springs 734 and its break contact to the fourth impulse pin on the receiver IDF, and the lamp ground conductor would have been connected to spring 744 and its make contact through the spring 745 and thence to the digit lamp 4. The fourth receiver IDF impulse pin, being multiplied to the second digit control wire instead of the first, would have caused the receiving of the digit 4 as a first digit to be registered as a fault, for the reason that the test circuits which were traced through spring 822 and its break contact to the digit 1 conductor would not have been connected to the fault wire, since the relay 704 would have been energized by the last impulse of the digit and the contact 733 would be made instead of broken. Therefore the relay 211 would not be short circuited and would energize in series with the relay 210. The relay 210 being marginal will not energize in series with relay 211. Relay 211 upon energizing, at springs 260 opens the ground circuit to the impulse springs 244 of the relay 205, thereby preventing the impulsing of relay 205 from having any effect upon the receiving mechanism. The spring 260 closing a circuit to its make contact closes a circuit from ground to the lamp ground conductor which is projected through springs

741, 742, 743, 744, and 745 through the fourth impulse lamp to battery. With a branch circuit through spring 615 and its make contact, through the lamp ground conductor 2, through spring 833 and its break contact, through the digit lamp 1 to battery. The relay 211 upon energizing further closes a circuit from ground through resistance 262, through spring 259 and its make contact through the impulse wire leading to the director. A circuit is completed through the grounded resistance 262, spring 259 and its make contact, impulse wire through relay 702 of the director, through wiper 719 now in engagement with last digit 80 register, through the magnet of that register to grounded battery. The relay 702 energizes over this circuit thereby preventing the director from cutting off. The high resistance of 262 prevents the digit register motor magnet from energizing in series with that resistance and relay 702. The director proceeds to impulse the remaining digits of the call number, but since the ground has removed from the impulse springs 205, this impulsing is without effect. The lamp ground conductor is further multiplied to the audible signal 412, which sounds to call the attendant's attention to the fault. The grounded lamp conductor has lighted the fourth impulse lamp, the first digit lamp, and sounded the audible signal calling the attendant to the test set-up, who will investigate the trouble. The attendant will note the director being tested, that being indicated by the director number lamp which is lighted from the grounded director selector wiper 222 through the obvious circuit to the director number lamp, will note that the test A is being applied to that director, the test A lamp being lighted in parallel with the test set-up relays 601 and 602 by the wiper 411 of the test selector, will note that the first digit defaulted by sending four impulses. The attendant will look at the record chart, giving the correct number for test set-up A and will note that the first digit should have contained three impulses instead of four. The ground placed on the impulse conductor by the fault relay 211, prevents the director from cutting off and releasing itself from the test set, and furthermore prevents the director from restoring to normal so that the attendant will find the director set just as it was when it sent out the faulty digit. The attendant upon finding the trouble with the director, will repair the trouble, and if he desires to exercise that director, will operate the key springs 241 to cut off the director selector motor magnet thereby permitting him to exercise the director in a manner which will be explained hereinafter. Having repaired the director, the attendant operates the fault release key 261, removing ground from the re- 130

lay 209, which was locked to the start ground through to this key and springs 258 and 253, allowing that relay to restore and at spring 255 remove the ground from the fault conductor. Relay 209 on restoring also removes the ground from the holding conductor thereby unlocking the receiving counting relay as explained hereinbefore, thereby permitting the receiving mechanism 10 to be restored to normal in readiness for the next call. Removal of high resistance ground from the impulse wire permits the director to restore and put itself in readiness for the next call. The test sending 15 mechanism is again brought into play to reset the director with the test set-up A, whereupon the test set is repeated.

Receiving the second digit.

20 Returning now to the sending of the first digit 3 in the set-up previously explained assuming that that digit was received correctly, the director will proceed to send the second digit of the call number. The second digit being a 4, the impulse counting relays 701 to 704, inclusive, and 712 to 715, inclusive, will be locked in energized position in a manner explained in connection with the receiving of the first impulse. After the springs 856 of the director have short circuited the impulsing springs, the pulsing relay 205 comes to rest energized allowing the test relay 207 to restore after a brief interval whereupon ground is projected out 25 over the fault conductor in the manner previously explained, to the spring 734, which is now resting against its back contact, thence over the fourth impulse pin on the receiver IDF, through the jumper to pin 2^b, through the springs 618, to pin 2^b, through the jumper to the digit control wire 30 digit 2, thence through the springs 820 through spring 827 and its break contact, through springs 822 and its make contact 35 to the test conductor, the ground being projected back over the test conductor to short circuit the fault relay 211 as hereinbefore explained. The successful reception of the digit causes the relay 210 to be energized 40 to unlock the relay 209, which removes ground from the holding conductor thereby restoring the counting relays to normal as before.

Third and fourth digits.

55 In a similar manner the third digit of the call number, in this case a 3, is received, the fault ground being connected to the test conductor through the third digit control wire, and after that the fourth digit, in this case a 1, is received in a similar manner. After the reception of the fourth digit, the digit control relays 801, 802, 803 and 804 60 will be energized, as will the counting relays 805 to 808, inclusive. The test con-

ductor will therefore be connected through spring 822, 827, 831, and 835 and their respective make contacts to the fifth digit control conductor from which point it is connected to the switch conductor on the receiver IDF. 70

Director cuts off.

75 After the director has finished sending the fourth digit it cuts itself off in the well known manner by placing a ground impulse wire, which ground is projected back to the springs 230 and 259, through the springs 328 and its make contact of the pulsing relay 304 and thence over the switching conductor to the switch pin on the receiver IDF 80 to which the test conductor is connected, as recited above so that that ground is projected back over the test conductor to energize the relay 210 and to short circuit the 85 fault relay to prevent its energization as before. Relay 210 upon energizing opens the locking circuit of relay 20 as before, allowing that relay to restore and close springs 252. The test conductor ground, 90 however, is not interrupted when the relay 209 opens springs 255 as it was when that ground was extended to it from the fault conductor between digits of the call number, and when relay 209 has restored a circuit 95 is completed from the test conductor ground through springs 257, springs 252 to the winding of relay 208 to grounded battery. Relay 208 energizes over this circuit and at springs 251 closes a locking circuit 100 for itself to the grounded holding conductor H³. Relay 208 at springs 254 opens the previously described circuit from the start ground to relay 204, allowing that relay to release. Relay 204 upon releasing opens the 105 circuit of relay 203, the latter relay, however, remains in its energized position for a moment because of the copper slug on its core. The restoration of relay 204 opens the circuit of relay 201 at springs 242, permitting that relay to restore and release the director upon which the successful test has just been completed. Relay 204 at spring 110 243 and its break contact closes a circuit traceable from that spring through springs 236, through springs 240, through the winding of the magnet of 213 of the meter to grounded battery. The meter energizes over 115 this circuit to register a completed test. In parallel with the above circuit for the meter is a circuit from grounded spring 243 to springs 241 to the director step conductor, DS step 1 through springs 922, to director step conductor DS step 2 through the winding of test director selector motor magnet 120 212 to battery. Magnet 212 energizes over this circuit and prepares to advance the wipers 220 to 225, inclusive, to the next set of bank contacts, to which are attached 125 trunks leading to the next director of the 130

group, say director No. 2 for example. Relay 203 then restores and at springs 237 and 238 removes the ground from the holding conductors H^3 and H^4 , allowing all relays which were locked up thereto to restore to normal. When the relay 203 restores, the above traced circuit to the motor magnet 212 is opened, allowing that motor magnet to restore and step the wipers ahead one 10 step.

Director busy setting a call.

Assume for the moment that the director now is busy setting up a call, the springs 832 of the director mechanism will be closed 15 thereby placing a ground on the private conductor 451, which is connected to the contact to be engaged by the wiper 223 when the switch mechanism steps ahead. A circuit is then closed from this grounded private conductor through wiper 223, through spring 232 and its break contact, the relay 201 having deenergized when relay 204 restores through the winding of relay 202 to grounded battery. Relay 202 energizes and at 20 25 spring 235 prepares a point in the circuit of the director busy lamp. When the relay 203 removes the ground from the conductor H^3 , it unlocks the relay 208, which restores after an interval closing the contacts 254 to again 30 energize the start relay 204 of the test director selector. This relay having pulled up a circuit is now closed to the relay 203 through spring 243 as before, and from the spring 242 and its grounded make contact, 35 a circuit is closed through spring 235 and its make contact to the director busy lamp, indicating that the director is busy at the moment setting up a call. The test director selector in this case will camp on the busy 40 trunk waiting an opportunity to seize the director for test as soon as it has completed its function of transmitting the digits of the call number. When the director has finished, the spring 832 retracts and removes the 45 ground from the private conductor 451 thereby restoring relay 202, allowing the springs 235 to retract against their back contact thereby closing a circuit from spring 242 and its grounded make contact to spring 235 and 50 its break contact, through the winding of relays 201 and 202 in series. Relay 201 energizes over this circuit to connect the director trunk on which wipers 220 to 225 are resting to the test set mechanism, which repeats the 55 above test A in the manner already described.

Director permanently busy.

In a similar manner test A is repeated on 60 all of the directors, the test director selector stepping its wipers one step at the completion of each successful test to seize the next director in regular order. It may happen that one of the directors in the group is made 65 permanently busy by means of its director

busy key, in which case the test set mechanism will not wait for that director to become idle, but will skip it and go on to the next. If a director is made busy by means of its busy key a circuit is completed from 70 ground through the lower springs of the director busy key, through the director busy conductor to the wiper 225, of the test director selector through the springs 234, through the winding of motor magnet 212 75 to grounded battery. The motor magnet 212 energizes over this circuit and at spring 234 breaks its own circuit, allowing the magnet to deenergize and advance the wipers 220 to 225, inclusive, to the next set of bank contacts. It will be noted that the ground picked up by the wiper 225 to step the test director selector off the contacts of a permanently busy director is also projected over the test selector step 2 conductor through 80 the winding of relay 402 to grounded battery to energize that relay. At springs 416 relay 402 places a ground on the H^3 conductor in multiple with the ground placed thereon through springs 239 and 237. This multiple 90 ground locks up relay 209 to prevent the test director selector from restoring to normal until its wipers rest on the bank contacts of an idle director or a director busy in the actual setting of a call.

Changing the test set-up.

When the test set mechanism has completed a successful test on the last director of the group, the director step magnet 212 100 is energized as before, to advance the wipers to the next bank contact. From this bank contact through the wiper 225 a circuit is completed from grounded battery through magnet 212 to spring 234 and its break contact, to wiper 225, now in engagement with the bank contact to which is connected the tests selector step conductor over that conductor through the winding of relay 403 to ground. Relay 403 energizes over this circuit, but the motor magnet 212 is prevented from energizing by the relatively high resistance of the relay 403. Relay 403 upon 110 energizing closes a circuit from ground through springs of key 420 to spring 417 and its make contact, through the winding of motor magnet 404 of the test selector mechanism, energizing that magnet, preparatory to advancing the wipers 410 and 411 115 to the next bank contact. Magnet 404 upon 120 energizing at spring 418 and its make contact closes a circuit from the grounded key spring 420 through spring 417 and its make contact, through to the test selector step conductor, which circuit excludes the relay 125 403. The motor magnet 212 of the test director selector energizing over this latter circuit and at springs 234 breaks the circuit of itself and relay 403. Relay 403 falls back and opens the circuit of magnet 404 which 130

deenergizes to advance the wipers 410 and 411 to the next bank contact. The magnet 212 falls back to advance the wipers 220 to 225, inclusive, to the next set of bank contacts, to which is connected the first director of the group. It will be understood, of course, that if there are more bank contacts in the bank over which the wiper 225 is driven than there are directors in the group, 5 the idle contacts are made busy by connecting them to ground potential, in which case the magnet 212 interrupts its own circuit and buzzes around in the well known manner until the wipers 220 to 225 are resting 10 on the contacts leading to the first director of the group. In the test selector the second bank contact engaged by the wiper 411 is also connected to the test A in the drawings. This is done merely by way of example as each bank contact in that bank could be led to a different test set-up relay if it was desirable to do so. With the set-up as shown in the drawings, the test set mechanism will now start out and again apply the test A to all of the directors in the group, energizing the above circuit to advance the test selector one step immediately after the last director in the group has been successfully tested. With the banks of the 20 test selector multiplied as shown in the drawing the test A will be applied six times as the wiper 411 moves from contact A to B, and the test B will be applied eight times as the wiper moves from the C to D and the test 25 C will be applied five times as the wiper moves from E to F with the test G applied only once. The particular number of times that these tests are applied is arbitrary, and in all probability they would not be applied 30 as many times as shown in the drawing. Inasmuch as the invention involves only three main types of tests, it will be advisable to show this test selector bank so multiplied in order to more fully bring out 35 the complete working of the testing equipment.

Exercising a director.

As was mentioned above it may be necessary for the switchman to exercise a director after he has repaired it or whenever he thinks it may be functioning erratically. In order to do this he operates the consecutive test key 241 to open the springs 241 there- 40 by opening a point in the director selector step circuit, so that when the test set completes a successful test on a director, and relays 203 and 204 deenergize to release the test setting equipment to normal, the previously described circuit to the stepping magnet 212 of the director selector is not completed. The testing mechanism after restoring itself to normal, unlocks the relay 204 which again closes the circuit to relay 204 45 to start the test. The test is then reapplied

to the director upon whose trunk the wipers 220 to 225 are standing in the manner which has been hereinbefore explained.

Routining a single director.

70

The switchman may desire to further exercise the director he has repaired by applying all of the routine tests to it. To do this he sets the mechanism for the exercise test explained above, and then operates the director routine key 226. When the relay 204 deenergizes and during the interval that relay 203 remains energized, a circuit is closed from grounded spring 243 and its break contact, springs 236, springs 226, 75 over the test selector step 3 conductor, through the winding of magnet 404 to grounded battery, energizing the magnet 404 to prepare to advance the wipers 410—411 one step. When the relay 203 falls back an instant later, the above circuit is broken at springs 236, allowing the magnet 404 to restore to advance the wipers 410—411. The wiper 411 closes a circuit to one of the groups of test set-up relays, energizing those relays to control the test as explained above.

Test set-up B.

95

The test set-up B is assumed to be similar to that shown in test set-up A in Fig. 6, the only difference being that the sender IDF and the receiver IDF are jumpered differently so that the test set mechanism will send into and receive from the director 100 a different set of numbers. This set-up involves no new features over those shown in Fig. 6 and it is therefore thought unnecessary that they be repeated at this time.

Test set-up C.

105

When the wiper 411 advancing as explained heretofore, reaches the bank contact C, it closes the circuit to the test set-up relays 901 and 902 shown in Fig. 9 of the drawing. By substituting Fig. 9 for the Fig. 6 in the layout as shown in Fig. 11, the drawings will show the circuits to be employed in this test C. The main point of difference between the test set-up C and the test set-up A is that the former applies the same test twice to each director before the director selector is stepped ahead to seize the next director. In the director mechanism shown in the first of my above mentioned copending applications, there are a plurality of digit registers, which are stepped ahead by the impulses of the last three or four digits of the call number. The construction of the switch used for these digit registers is such that if the wiper mechanism becomes sluggish on release, the register may not release properly if set to call the digit 1. Accordingly, the test set-up is arranged to dial the digits 111 into the 110 115 120 125 130

director mechanism, whereupon the director sends out the digits 111, and then cuts off. The wipers of the digit registers are now set to position 1 and if any of them fail to get back to normal, the failure will be caught by the next test, which is the test C immediately repeated upon the same director. That is the test C is repeated on each director twice before the test director selector selects out and picks up the next director. If any of the wipers of the digit registers have failed to get back to normal they will receive an impulse when the test mechanism sender again sends the digits 111 into the director and will step forward one step from the position in which they rest, the faulty register thereby being stepped to the second position. Then the director starts to send back the digits 111 the digit controlled by the faulty digit register will contain two impulses instead of one and as a consequence the testing loop of the test set mechanism will not be completed and the fault will be recorded. As was noted in Fig. 6 the director selector test conductor was run from the make contact to the relay 203 through a pair of normally closed springs marked 922 in the Fig. 6, and thence back to the motor magnet of the director selector. When test C is being made on the director these contacts 922 are opened by the relay 903, so that the director selector motor magnet 212 does not receive the impulse of ground when the relay 204 deenergizes, but rather that impulse is fed into a relay in the test set-up group. Thus if the first test of the director is successfully completed does not advance the director selector wipers to the next director, but merely sets up a relay in the test set-up group. The test is therefore repeated on the director and when the test is successfully completed and relay 204 again falls back and sends another impulse of ground over the director selector step conductor, the circuits of the test set-up group are now closed in such a manner that the second impulse is delivered to the director selector motor magnet 212 to step the wipers to the next group of contacts.

Referring now to Fig. 9, the test set-up relays 901 and 902 are controlled over the test control conductor C from the banks of the test selector through the medium of wiper 411, which obtains its ground from the key spring 420 and its break contact. The relay 901 upon energizing jumpers the sender IDF so that the test mechanism is arranged to send out the digits 111 and then stop. The relay 902 upon energizing closes the springs 916 to 920, inclusive, which jumper the receiver IDF so that the test set mechanism is arranged to receive digits 111 and then cut-off. Relay 901 also closes the circuit from ground to spring 915 and its make contact

through the winding of relay 903 to battery, energizing that relay and closing it to close the circuit from grounded springs 921 to the start and start 1 conductors, to start the test mechanism in motion in the manner herein-before explained. 70

The test set mechanism then pulses into the director and the director pulses back into the test set mechanism in the manner already explained and when the test mechanism has completed the test following the reception of the last impulse of the last digit, the circuit to relay 204 is opened as before explained, allowing that relay to fall back to close a circuit from grounded spring 243 and its break contact, spring 236 and its make contact, the relay 203 not yet having had time to restore, key springs 241 to the director selector step conductor 1 through the spring 922 and its make contact, through spring 924 and its break contact, through the winding of relay 904 to grounded battery. Relay 904 energizes over the circuit, locking itself to ground through the upper winding of relay 905, through springs 923 and 926. Relay 905 energizes through its upper winding in series with the relay 904, and at springs 924 and 925 prepares the circuit to connect director selector step conductor 1 to director selector step conductor 2. The test mechanism sends out the test again to the director at the completion of which the relay 204 again falls back closing a previously-described circuit to place ground on the director selector step conductor 1, the circuit now being completed through spring 922 and its make contact, spring 924 and its make contact thence over two parallel paths, the one through the winding of relay 906 and the lower winding of relay 905 to grounded battery and the other through the springs 925 to the director selector step conductor 2 and thence through the winding of director selector motor magnet 212 to grounded battery. The magnet 212 energizes to prepare to advance the wipers 220 to 225 to the next bank contact in the well known manner. Relay 906 energizes over this circuit opening the previously traced locking circuit of relay 904 at the springs 925. When the relay 203 deenergizes, a brief interval after its circuit was opened by the relay 204 falling back, the circuit to relay 906 is opened at spring 236, allowing that relay to restore, and allowing the magnet 212 to restore to advance the wipers to the next bank contact. The test is then repeated on the next director two times before the test director is stepped on to the third director. When the last director of the group is reached, the circuit previously traced to the winding of the test selector motor magnet is again completed allowing the motor magnet to energize and prepare to advance the wipers 410 and 411 of the test selector to the next contact. In 123

asmuch as the next contact is also multiplied to the test set-up C, the test will again be repeated on all of the directors. The test C is repeated on the directors in the foregoing 5 manner until the wiper 411 of the test selector has reached the contact "f" whereupon when the last director in the group has been tested for the second time and a circuit is again closed to the magnet 404 of the test 10 selector, the wiper 411 is advanced to contact "g" which is connected through to the test set-up relays of test D.

Test set-up D.

15 The test set-up D is arranged to test the time limit release function of the director. Inasmuch as there are a relatively small number of directors in an exchange, provision has been made to prevent a subscriber 20 from willfully or accidentally monopolizing one of the directors for an unduly long period of time. In the event that the subscriber removes his receiver from the telephone, and fails to dial, he is tying up a 25 director needlessly. Or, if the subscriber after dialing one or two digits of the call number, fails to dial the remaining digits, he is again tying up the director, preventing its use by other subscribers. It would be 30 possible for a few subscribers with malicious intent to tie up the entire office by simply removing their receivers from the hook and failing to dial at all or dialling only part of a number. To prevent this kind of practice, and to prevent director tie-ups from line 35 permanents, a time limit release mechanism is provided, its duty being to release the director from the faulty line after a definite time interval. If the subscriber has, after 40 seizing the director, dialled a portion of the digits of the call number, and the director has started to set up the call, in addition to the director there will be a switch train of one or two switches held up pending the 45 dialling of the next digit by the subscriber. When the time limit release mechanism releases the director, it releases the switch train also, and immediately seizes the first selector, that was used before, and dials a 50 special number, which may either lead the call to an intercepting operator or return a busy signal to the calling subscriber to inform him that his connection cannot be completed. By substituting Fig. 10 for Fig. 6 in 55 the drawings as shown in Fig. 11, the circuit arrangement of the test set when test set-up D is employed is shown. Test set-up D arranges the test sender to send the digits 99 into the director and then to stop. The director 60 sends back the digit 9 and then stops. After an interval determined by the time interval mechanism, the director switches through, releasing the test set, and then reseizing it and sending out the digit 1. Referring again to Fig. 10, it will be noted that

the start conductor and the start 1 conductor which were shown in Figs. 6 and 9 as connected together through the normally closed springs 1024, are now separated when the test set-up relays 1001 and 1009 are energized. The start 1 conductor is immediately grounded to start the test director selector in operation to seize the first director to be tested, however, the start 1 conductor is not grounded at this time. When the time pulse mechanism TP rotates half a revolution from the position in which it is shown in Fig. 2, a circuit for the relay 1002 may be traced from ground through the time pulse mechanism TP, through springs 249 over the 70 time pulse conductor through springs 1025, through springs 1054, through the winding of relay 1002 to grounded battery. Relay 1002 energizes over this circuit and at spring 1029 throws a ground out on the start 1 conductor, to start the test sender mechanism in motion in the manner hereinbefore explained. The test sender is prevented from starting until the above mentioned time pulse is received in order to insure a full time interval in the period during which the director is waiting for either another digit or the time interval. The test set mechanism sender is arranged to send the digits 99 into the director and to wait for the time limit release to function. When the director receives the digits 99, it sends back the digit 9, operating the pulsing relay 205 in the manner previously described to send impulses of ground out over the pulse wire. Those grounded impulses being conducted through spring 1045 and its break contact to the pulse 2 wire and thence through the springs 763 to the test relay conductor to pull up the test relay 207 as explained hereinbefore. The pulses of ground are also fed through the receiver impulse counting relay in the manner previously explained, energizing the relays 701 to 709, inclusive, and the relays 712 to 720, inclusive, as explained 95 hereinbefore. When the springs 856 of the director short circuit the interrupter springs 813, the pulsing relay 205 of the test director selector comes to rest energized opening the circuit of the test relay 207, that relay falling 100 back after an interval to project ground out over the fault wire in a manner already explained. The fault ground is projected through spring 730 and its make contact 739 and its break contact to the ninth impulse 105 pin of the receiver IDF through the jumper in the first digit pin 1, through the springs 1027 through springs 1052, through the winding of relay 1014, to grounded battery, energizing the relay 1014, which prepares a locking circuit for itself in series with relay 1008 in the well known manner. The fault conductor is also projected through spring 1051 and its break contact, through spring 1025 and its make contact to the test conductor 110

to short out the fault relay 211 in the manner explained above. When the ground is removed from the fault conductor by the restoration of relay 209, the relay 1008 energizes in series with relay 1014 through the spring 1053 and the winding of relay 1008 to hold conductor 4. The energization of relay 1008 extends the time conductor through to the second digit counting relay 1013, so that when the next time pulse is received, relay 1013 is energized over the circuit from the grounded time conductor to spring 1050, spring 1046 and its break contact to the winding of relay 1013 to battery. Relay 1013 upon energizing at springs 1048 prepares a locking circuit for itself in series with relay 1007, and when the time pulse mechanism removes ground from the time conductor, relay 1007 energizes in series with relay 1013 over the circuit including spring 1040 the winding of relay 1007 to grounded hold conductor 4. Relay 1007 upon energizing closes a circuit to relay 1011, which may be traced from grounded spring 260 and its break contact, through springs 244 and 244' through spring 247 and its make contact over the release test conductor through springs 1047 through springs 1044, through the winding of relay 1011 to grounded battery. Relay 1011 upon energizing prepares at spring 1038 a point in the circuit of relay 1005.

The time pulse releases the director.

35 The test set mechanism now remains idle until the next time pulse is received at which time ground from the time conductor is projected through springs 1050, spring 1046 and its make contact, through springs 1041, through the winding of relay 1012 to grounded battery. Relay 1012 energizes over this circuit and locks itself to hold conductor 4 in series with relay 1006 and springs 1043. Relay 1006 does not energize as long as the time conductor is grounded. Relay 1012 upon energizing at spring 1044 opens the previously described circuit from the release test conductor to relay 1011, allowing that relay to deenergize. Relay 1011 being slow to release because of the copper slug upon its core does not deenergize immediately, but holds its armature in energized position for a definite interval after the current through its coil is cut off. 45 If the ground remains on the time conductor long enough to permit the relay 1011 to deenergize before the relay 1006 energizes, the cutoff feature of the director time limit releases is tested and recorded as successful. 55 The last mentioned time pulse is received by the director and by the test mechanism simultaneously whereupon the director functions to open the outgoing loop circuit thereby allowing the relay 205 to drop back. Relay 205 upon dropping back closes a circuit

to place ground on the pulse conductor, picking up the relay 712, which prepares at spring 752 the locking circuit as before. However, the relay 712 does not lock up this time because the hold conductor is not 70 grounded, the relay 209 being deenergized at the time and the spring 256 consequently being open. Inasmuch as the relay 1006 has not yet energized the pulse conductor is not connected to the pulse 2 conductor and consequently ground is not projected back through spring 763 to the test relay conductor to energize the test relay 207 of the test director selector. After a brief interval the time impulse conductor is no longer 80 grounded, and the pulsing relay 205 of the test director selector is again energized, and at spring 244 breaks the previously described circuit through which the pulse wire was grounded. Relay 712 thereupon falls back without effect at this time. Shortly before the time pulse conductor was ungrounded, the relay 1011 deenergized and at spring 1038 opened the circuit of relay 1005, so that when relay 1006 is energized at the completion of the time pulse, the circuit through relay 1005 cannot be completed. Energization of relay 1006 at spring 1042 closes a point in the test circuit which will be explained presently, and at spring 1041 opens the point in the time pulse circuit so that additional time pulses will be without effect on the test mechanism.

The director sends the digit one.

Immediately after the director has cut off and released the switch train, in this case comprising only relay 205 of the test director selector, and then reseized the first selector, in this case also the test director selector, 105 it impulses once to send out the digit 1. Relay 205 falls back as before projecting the ground from spring 260 through spring 244 and its break contact, springs 248 and its make contact to the pulse conductor, 110 energizing the relay 712, which prepares to lock itself in series with relay 701 as before. This ground is also projected over the pulse conductor through spring 1040 of the relay 1006 to the pulse 2 conductor, and thence 115 back to the spring 763 to the test relay conductor, to energize the test relay 207. When the spring 856 of the director has again shorted the impulse springs 813 after the transmission of the digit 1, relay 205 comes 120 to rest energized opening the circuit of test relay 207, which restores after a brief interval and projects ground out over the fault conductor in the manner already described. The relays 701 and 712, having 125 been energized by the simple impulse of ground on the pulse conductor, the fault conductor is now connected through spring 730 and its make contact through spring 731 to the first impulse pin of the receiver IDF, 130

which is jumpered to the second digit pin, and thence through spring 1031 and its break contact, to springs 1037, spring 1042, spring 1050 and its make contact to spring 1026 to the test conductor, the ground being projected back over the test conductor to short out the fault relay 211 in the manner explained hereinbefore, to record the successful reception of the digit 1. A multiple branch from the spring 1031 of the foregoing circuit projects that ground to spring 1032, through the winding of relay 1010 to grounded battery, energizing the relay 1010 which at spring 1033 prepares a locking circuit for itself in series with relay 1004 in the well known manner. At the completion of the test, relay 1004 energizes. Immediately after transmitting the digit 1, the director mechanism cuts itself off projecting ground back on the impulse wire, that ground being projected over a circuit including spring 259 and its break contact, spring 238 and its make contact, switching conductor multiplied at the receiver IDF to the spring 1031 and its make contact thence over the previously traced circuit including springs 1037, 1042, 1051, and 1026 to the test conductor to energize the relay 210, which prepares the test director selector cut-off circuit in the manner explained in detail hereinbefore. The time limit release test having been successfully completed on the director then being tested, the test director selector releases that director and seizes the next director of the group in the well known manner.

Time pulse release defaults.

Referring back now to the reception of the second time pulse which operated the magnet 1012 to open at springs 1044 the circuit of the slow to release relay 1011. Assume for the moment that the time pulse was not sufficiently long to allow this relay 1011 to restore. This relay being adjusted carefully restores in the minimum time during which a director mechanism and switch train can be successfully released, that time being the time that the ground must be maintained on the time pulse wire. If the ground is removed from the time pulse wire before the relay 1011 is deenergized the relay 1006 energizes in the manner hereinbefore explained in series with the relay 1012, and at spring 1039 closes a circuit from grounded holding conductor H^4 through springs 1039, through springs 1038, through the winding of relay 1005 to grounded battery. Relay 1005 energizes over this circuit and locks itself to the holding conductor H^4 , through springs 1036 over a circuit independent of the springs 1038. The time pulse conductor now being ungrounded, the director again seizes the test set mechanism by closing the loop to relay 205 and im-

mediately transmits the digit 1 in the manner just explained. At the completion of the transmission of the digit 1, the ground projected out over the fault wire, and which must be conducted through the test wire to short out the fault relay 211, is projected over a circuit which includes spring 1037 and its break contact, that circuit having been just described. If the relay 1005 was energized, this spring 1037 will be moved away from its break contact and the fault relay 211 will deenergize to denote the unsuccessful test. Energization of relay 211 projects ground over the lamp ground conductor from grounded spring 260 and its make contact that ground being projected through spring 1049 and its make contact, spring 1034 and its make contact over the second digit lamp conductor DL^2 , through the second digit lamp to battery, lighting that lamp to notify the attendant that the second digit failed. The lamp ground conductor also being multiplied through the counting relay chain of the receiver impulse counting relays to light one of the impulse lamps. The particular one of the impulse lamps which will be lighted depends somewhat upon just how much too short the time impulse is. The first register of the switch mechanism was set on the digit 9 and that register must restore to normal and be reset upon the digit 1. If the time impulse is too short to allow that register to properly restore, its motor magnet will again be energized and stop it somewhere before it gets back to the normal position. The test set mechanism then instead of sending the digit 1, will have sent out some other digit, which has set up the counting relays, thereby causing the impulse lamp corresponding to the number of impulses sent to be lighted at this time. Ground on the lamp ground conductor also causes the audible signal 412 to be sounded to call the attendant to the test set to locate and remedy the trouble.

Metering the tests.

As was mentioned above, I have provided the meter mechanism controlled by magnet 213 on which the successful tests are counted. I have also provided the meter mechanism 214, which is controlled through springs 263 of the fault relay 211 in the obvious manner. This meter which is operated each time the fault relay is energized, records the number of faults found by the test mechanism.

Miscellaneous.

If the attendant desires to apply a particular test on one of the directors, he operates the director selector step key, thereby operating the key springs 239 and 240. The spring 239 closes a circuit from ground through that spring and its make contact

to the winding of the motor magnet 212 of the test director selector. Motor magnet 212 energizes over this circuit and prepares to advance the wipers 220 to 225 to the next bank contact set in the well known manner. When the attendant releases the spring 239, the magnet 212 deenergizes advancing the wipers. By repeating this operation the attendant is able to pick out any director of the group, provided that director is not permanently busy. The attendant is informed which director the test director selector is in a position to test by means of the director number lamp which is lighted over a circuit including the wiper 222 of the test director selector. This wiper rotates with the wiper group and lights the director number lamps consecutively to indicate with which director the test director selector is associated at the moment, enabling the attendant to pick out a particular director for test. It may happen that during the application of the routine to the directors, the attendant desires to omit one of the tests, and to reapply a certain other one of the tests to the group. Assume for the moment that the wipers 410 and 411 of the test selector are in such a position that the wiper 411 is encountering the bank contact "e". If the attendant desires to omit the test C, he may step the wipers 410 and 411 over that test by operating the key 420 by operating the key 419, closing a circuit from ground through spring 419, through the winding of motor magnet 404 to grounded battery. This magnet energizes over the above traced circuit and prepares to advance the wipers 410 and 411 to the next bank contact when the circuit to the magnet is broken. By repeating the operation of this key the wipers can be stepped to any desired bank contact. If, for example, the attendant desires to apply the test D, he continues the operation of key 419 until the test D light is lighted to indicate that that test is selected. The test D light lights over a circuit from ground through spring 420 and its break contact, through springs 417 and its break contact, through the wiper 411, now in connection with the bank contact "g", over the test D control wire through the relays 109 and 101 in series to grounded battery with the multiple connection through the test D lamp. If the attendant desires to omit some of the tests altogether or to step the routine be-

55 If the attendant desires to omit some of the tests altogether or to stop the routine before all the tests have been completed, he may do so and return the equipment to normal by operating the key 420. The operation of this key breaks the ground circuit to the wiper 411 thereby releasing the test set-up relays to which the wiper is connected at the time, and by the operation of the make contact, key 420 places ground on the bank 60 contact, key 420 places ground on the bank 65 swept over by the wiper 410, completing a

circuit through that wiper through the break contact at spring 418, through the winding of motor magnet 404, to grounded battery. Magnet 404 energizes over this circuit and

at spring 418 breaks its own circuit, allowing its armature to fall back and advance the wipers 410 and 411 to the next bank contact. This process is repeated until the wiper 410 encounters the idle contact as shown in Fig. 4.

While I have chosen to illustrate my invention in connection with a particular type of equipment and arranged to show particular test set-ups, I have done so merely by way of example and do not wish to be limited to the specific disclosures contained herein as there are many modifications which will be apparent to one skilled in the art, which can be made without departing from the scope of my invention.

Having thus described my invention, what I consider new and desire to have protected by U. S. Letters Patent is pointed out in the appended claims.

What is claimed is:

1. In a telephone system, a series of translators arranged to translate and retransmit the digits of a telephone number, a testing mechanism therefor, said mechanism having means for automatically sending a number to the translators in consecutive order and for receiving the translated number therefrom, and means in said mechanism for stopping the sending of further digits and holding a translator when that translator fails to properly translate or retransmit any digit. 95

2. In a telephone system, a group of translating devices arranged to register, translate and retransmit the digits of telephone numbers, a test mechanism, means for automatically connecting said mechanism to one of said translating devices, means in said mechanism for automatically testing a function of said device by transmitting a number thereto and receiving a number therefrom, means including a relay energized upon the successful receipt of each digit of said number and to record the successful completion of said test, and means for then automatically releasing the seized translating device and seizing the next translating device of the group. 100 105

3. In a telephone system, a group of translating devices arranged to register, translate and retransmit the digits of telephone numbers, a test mechanism, means for automatically connecting said test mechanism to said translating devices in consecutive order, means in said mechanism for automatically performing in steps a test of one of the functions of a seized device, means including a relay energized to record the successful completion of each step of said test, and means then automatically operative after the last 110 115 120 125 130

step of said test to release the seized translating device and to seize the next translating device of the group.

4. In a telephone system, a group of translating devices arranged to register and retransmit the digits of telephone numbers, a test mechanism, means for automatically connecting said test mechanism to said translating devices in regular order, means in said 5 test mechanism for automatically testing a function of said seized device, for recording the successful test and for releasing the seized mechanism, means for causing said connecting means to reseize said translating 10 device and repeating said test, and means operated at the completion of the successful repetition of said test for releasing said device and for causing said connecting means to seize the next translating device of the 15 group.

5. In a telephone system, a group of translating devices arranged to register and retransmit the digits of telephone numbers, a test mechanism, containing a plurality of 20 test controls, a test control selector, means for connecting said test mechanism to each of said translating devices in consecutive order, means for energizing one of said test controls through said test selector to arrange 25 the mechanism for a particular test, means responsive to the energization of said control for operating said connecting means to seize one of said translating devices for applying the selected test thereto and for re- 30 leasing that device and seizing the next after the successful completion of said test, and means automatically operative after the test on the last translating device of the group for operating said test selector to release 35 said energized test control and to seize the next of said controls, and for causing said selected test to be applied to said translating devices in consecutive order.

6. In a telephone system, a group of translating devices arranged to register, translate 40 and retransmit the digits of telephone numbers, a test mechanism, a plurality of test controls in said mechanism, a control selecting switch, means for connecting said test 45 mechanism to each one of said translating devices in consecutive order, means for energizing one of said test controls through said selecting switch, means governed by said selected control for applying the selected 50 test to said connected translating device, and means automatically operated upon completion of said test on the last device of said group for releasing said energized control and for operating said selecting switch to 55 select the next of said controls.

7. In a telephone system, a group of translating devices arranged to register, translate 60 and retransmit the digits of telephone numbers, a test mechanism, a plurality of test controls in said mechanism, a test select-

ing switch, means for automatically connecting said test mechanism to one of said translating devices, means for automatically testing the functions of said device, and means for arranging said testing mechanism 70 so that upon the successful completion of said test, said selecting switch is automatically stepped ahead to select the next test control.

8. In a telephone system, a group of translators arranged to register and retransmit the digits of telephone numbers, and to respond to a time pulse to release a partly established connection and dial a special one if delay between successive digits exceeds a 80 definite interval, a time pulse mechanism for measuring that interval, a test mechanism, a translator selector for connecting said test mechanism to said translators in consecutive order, said test mechanism being arranged to send part of the digits of a call number to said translator and to delay, 85 means in the test mechanism responsive to the time pulse which releases the translator for timing said release and for checking the accuracy of the special number subsequently transmitted, and means responsive to a translator failure for preventing the release of any operated equipment and for sounding an alarm.

9. In a telephone system, a group of translators arranged to register and retransmit telephone numbers and further arranged to respond to a time pulse to release a partly established switch train and call a special 90 number if no digits are received during a predetermined time interval, a test mechanism arranged to send part of the digits of a call number into the seized device and to delay the sending of the remaining digits, 95 means in said mechanism responsive to said time pulse that releases said translator for arranging said mechanism to check said release and the subsequent dialling of the special number, and means responsive to a 100 faulty operation for preventing the release of any operated equipment and for sounding an alarm to call attention to the fault.

10. In a telephone system, a plurality of translating devices arranged to register and retransmit the digits of telephone numbers, a test mechanism, a translator selector for connecting said test mechanism to said translators in consecutive order and arranged to indicate which translator is connected for test, 110 a plurality of test controls in said test mechanism, means for seizing one of said test controls and for indicating which control is seized, said test mechanism being responsive to said control to apply a test to said translator, means in said test mechanism for registering the retransmitted digits and for testing the accuracy of each digit, means responsive to a fault for preventing the release of any operated equipment, means for 115 120 125 130

indicating which digit was faulty and means for indicating in what manner said digit was faulty.

11. In a telephone system, a plurality of translating devices arranged to register and retransmit the digits of telephone numbers a test mechanism, containing a plurality of test controls and means for selecting and energizing them, a translator selector for connecting said test mechanism to said translators consecutively, means in said mechanism for testing the functions of said translators, means for always indicating which translator is being tested and what test is being applied thereto and means operative in case a fault is found for indicating the exact nature of that fault.

12. In a testing mechanism, a sending device and a receiving device, means for connecting the mechanism to a translating device which is to be tested, means in said mechanism operative to arrange the sender to send certain digits into said translating device and to arrange the receiver so that certain digits must be received from said device, correct and fault relays one of which is automatically operated over a loop extended thru said receiver at the end of each digit, to indicate the accuracy of that digit, and means for rendering the test mechanism unresponsive to further digits unless the former digit was received correctly.

13. In a test mechanism, a receiving device comprising counting relays by means of which the impulses of a digit are counted and digit control relays through which the correct number of impulses to be contained in said digit is determined, means for sending impulses to said counting relays, a fault relay and a correct relay, a test relay, a circuit for said fault and correct relays in series controlled by said test relay, a parallel circuit similarly controlled and arranged to short circuit said fault relay and to energize said correct relay if said digit was received correctly and means controlled by said correct relay for releasing the operated ones of said counting relays and to operate said digit control relays, setting them to govern the reception of the next digit.

14. In a test mechanism, a receiving device comprising counting relays by means of which the impulses of a digit are counted and digit control relays through which the correct number of impulses to be contained in said digit is determined, means for sending impulses to said counting relays, a fault relay and a correct relay, a test relay, a circuit for said fault and correct relays in series controlled by said test relay, a parallel circuit similarly controlled and arranged to short circuit said fault relay and to energize said correct relay if said digit was received correctly, said parallel circuit being incompletely controlled and fault relay being energized

if the digit was incorrectly received and means controlled by said fault relay for preventing the release of any operated equipment and for sounding an alarm to call the attention to the fault.

15. In a telephone exchange, a plurality of translating devices, a test mechanism for testing the functions of said devices including a receiving device containing a pulsing relay, a loop circuit for said relay being completed in the device that is being tested, said translating device being arranged to alternately open and close said loop to impulse said relay, to send a digit into said receiver, a series of counting relays, a test relay, a circuit for said counting relays and said test relay controlled by said pulsing relay, said counting relays being consecutively energized over said circuit by the impulses of the digit and said test relay being maintained energized throughout the impulsing and allowed to drop back at the end of the digit, a digit control relay group, through which circuits are completed to arrange the receiving device so that certain digits must be received in certain order, a fault relay and marginal correct relay, a series circuit for said relays completed by the deenergization of said test relay, said relays being adjusted so that said fault relay will energize and said marginal relay will not energize over this series circuit, a parallel circuit similarly established by said test relay, which is completed through said counting, digit control, and set-up relay groups to short circuit said fault relay and to energize said correct relay if the digit was received correctly, and means controlled by said correct relay for releasing the operated ones of said counting relays and for energizing certain of said digit control relays to prepare the receiver for the reception of the next digit.

16. In a telephone exchange, a plurality of translating devices, a test mechanism for testing the functions of said devices including a receiving device containing a pulsing relay, a loop circuit for said relay being completed in the device that is being tested, said translating device being arranged to alternately open and close said loop to impulse said relay to send a digit into said receiver, a series of counting relays, a test relay, a circuit for said counting relays and said test relays controlled by said pulsing relay, said counting relays being consecutively energized over said circuit by the impulses of the digit and said test relay being retained energized throughout the digit and allowed to drop back at the end of the digit, a digit control relay group and a set-up relay group through which circuits are completed to arrange the receiving device so that certain digits must be received in certain order, a fault relay and a marginal correct relay in

a series circuit for said relays completed by the deenergization of said test relay, said relays being adjusted so that said fault relay will energize and the marginal relay will not energize over this series circuit, a parallel circuit similarly established by said test relay, which is incomplete in the counting relay group if the digit was incorrectly received to allow said fault relay to energize and means controlled by said fault relay for preventing the release of any operated equipment and for sounding an alarm to call attention to the fault.

17. In a telephone system, a plurality of translating devices, arrangements for marking the device artificially busy and actually busy, a test mechanism for applying a test to said devices, a translator selector for connecting said mechanism to said devices consecutively and for starting the operation of said test, means operative upon the successful completion of said test for causing said translator selector to release the seized device and to move to the next, and means in said selector for causing it to skip said artificially busy devices and to camp on an actually busy device until it becomes idle at which time such device is seized for test.

18. In a telephone system, a group of translators arranged to register, translate, and retransmit the digits of telephone numbers, a testing mechanism, means for automatically connecting said testing mechanism to said translators in consecutive order, means in said test mechanism automatically operated to arrange it to send certain digits into said translator and to arrange it to receive certain digits therefrom, counting relays responsive to impulses received from said translator to determine the digit, means controlled by said counting relays responsive to the reception of a digit other than those the mechanism is arranged to receive, for recording the faulty digit and the number of impulses it contained for rendering said mechanism irresponsible to further digits from said translator, and for preventing the release of said connection between said mechanism and translator.

19. In a telephone system, a group of translators arranged to register, translate and retransmit the digits of telephone numbers, a test mechanism containing a plurality of controls, selecting means for connecting one of said controls to said test mechanism, connecting means for connecting said test mechanism with said translators, one at a time in consecutive order, and means operated after the last translator has been connected to for operating said selecting means to release said connected control and to connect another control to said mechanism.

20. In a telephone system, a group of translators arranged to register, translate and retransmit the digits of telephone num-

bers, a test mechanism containing a plurality of controls, selecting means for connecting one of said controls to said test mechanism, a connecting switch having a plurality of bank contact set and wipers through which said test mechanism is connected to said translators one at a time, a control contact set accessible to said wipers after all of said first contact sets have been engaged, and circuits completed by said wipers and through said control contacts to operate said selecting means to release said connected control from said mechanism and to connect another thereto.

21. In a telephone system, a group of translators arranged to register, translate and retransmit the digits of telephone numbers, a testing mechanism, a plurality of controls for said mechanism, a control selector operated to select a control and to connect it to said mechanism, means for automatically connecting said mechanism to said translators one at a time and in consecutive order, said mechanism applying the test governed by said selected control to the translator, means responsive to the successful completion of said test for releasing said connected translator and stepping said connecting means into connection with the next translator, and means responsive to the release of said mechanism from the last translator of said group for releasing said selected control and selecting the next and connecting it to said mechanism.

22. In a telephone system a plurality of translators arranged to register, translate, and retransmit the digits of telephone numbers, a test mechanism containing devices for performing a plurality of different tests on said translators, selective means for determining which of said tests is to be applied, means for connecting said test mechanism to one of said translators and for applying the selected test thereto, means responsive to the successful completion of said test for releasing said connected translator and connecting to the next translator, and means responsive to the completion of a successful application of said test on the last translator of the group for automatically selecting another of said test devices and for applying that test to said translators which are reseized in the same order.

23. In a telephone system, a group of translators arranged to register, translate, and retransmit the digits of telephone numbers, a testing mechanism comprising a sending device, a receiving device, correct and fault relays and test set up relays, means for connecting said test mechanism to said translators in consecutive order, circuit means for energizing certain of said set up relays to arrange said sender to send a certain number into said connected translator and to arrange said receiver to receive a cor-

responding number therefrom, a testing circuit established at the end of each digit reapplying the same test to the same translator or for releasing that translator and receiving by said receiver to test its accuracy, seizing the next, to which the same test is and to energize the correct relay if said digit applied.
5 is correct, and means controlled by said correct relay upon energizing after the last digit of said number and dependent upon which of said set up relays are energized for

In witness whereof, I hereunto subscribe my name this 7th day of August, A. D. 1925.

MARTIN L. NELSON.
